(57) **CLAIM**

The ornamental design for apparatus for medical tests as shown and described.

DESCRIPTION

FIG. 1 is a left side view of an embodiment of an apparatus for medical tests;

FIG. 2 is a perspective view thereof;

FIG. 3 is another perspective view thereof;

FIG. 4 is a front view thereof;

FIG. 5 is a right side view thereof;

FIG. 6 is a back view thereof;

FIG. 7 is a bottom view thereof; and,

FIG. 8 is a top view thereof.

The broken lines shown in FIGS. 2, 3, 4, 6, and 7 illustrate portions of the apparatus for medical tests that forms no part of the claimed design.
